CHIN STRAP FOR A HELMET

Richard L. Woods, 1514 SW. 77 Terrace,
Oklahoma City, Okla. 73159

Filed June 11, 1973, Ser. No. 368,704

Term of patent 14 years

Int. Cl. D2—99

U.S. Cl. D2—260

FIG. 1 is a side elevational view of a chin strap for a helmet showing my new design, the strap is shown broken away for convenience of illustration;

FIG. 2 is a front elevational view thereof;

FIG. 3 is an elevational view of the side opposite that shown in FIG. 2;

FIG. 4 is an elevational view of the side opposite that shown in FIG. 1;

FIG. 5 is a top end view thereof; and

FIG. 6 is a bottom end view.

I claim:

The ornamental design for a chin strap for a helmet, substantially as shown and described.
